REFRIGERANT CONTROL DEVICE

Paul Haymond, Fairmont, W. Va.

Application July 23, 1936, Serial No. 92,217

13 Claims.

(Cl. 62—8)

The present invention relates to a refrigerant control device especially adapted for use in connection with the controlling of the refrigerant in the conventional compressor type refrigeration system.

In refrigerating systems of this character the method of controlling the refrigerant is by what is known as the low side float, the high side float, and the expansion valve. The low side float has the advantage of keeping the evaporator flooded with the refrigerant at all times. However, this advantage is somewhat offset by the variation of suction pressures which when decreased reduces the capacity and efficiency of the condensing unit materially. The low side float simply permits enough refrigerant to enter the evaporator to maintain a fairly constant liquid level. The refrigerant is permitted to enter the evaporator under any pressure less than the liquid refrigerant pressure of the condensing unit.

The expansion valve system permits the refrigerant to flow into the evaporator at a constant pressure below a predetermined setting. This system of control of the refrigerant permits higher condensing unit capacity and efficiency. However, it is practically impossible to obtain the ideal situation of having the evaporator in a flooded condition without the spilling over of the refrigerant into the suction line, which causes very inefficient operation. In this connection thermal regulators have been devised and are now in use which attempt to control the frost line on evaporators operated by expansion valves. A gas charged bulb is clamped to the suction line and connected to a bellows which varies the tension of the expansion valve actuating spring. The disadvantage of this system of controlling the refrigerant is that it is almost impossible to maintain the flooded coil without frosting or refrigerating the suction line.

It is therefore one of the objects of the present invention to provide a refrigerant controlling device which insures a flooded condition of the evaporator at all times and which will insure the feeding of the refrigerant to the evaporator at a constant suction pressure at a predetermined setting during the operation of the device.

A still further important object of the invention is to provide a refrigerant controlling device of this character which will maintain a more constant back pressure on the system of the compressor, evaporator type refrigerating system.

The present invention contemplates the provision of a float valve having a snap action mechanism to fully open and fully close the needle

valve controlling the flow of the refrigerant and to impose between the float valve and the refrigerant supply of the condensing unit a conventional type automatic expansion valve which will insure the feeding of the refrigerant to the evaporator at a constant suction pressure at a predetermined setting during the time the float valve is open. In other words, the present invention contemplates the combination of the low side float control and the expansion valve in a novel manner to obtain the advantages of each.

By combining the float valve and the expansion valve, a system of refrigerant control is obtained which has the advantages of completely flooding the evaporator with liquid refrigerant and the advantages of the expansion valve by supplying the refrigerant at a constant suction pressure. The efficiency of the evaporator and the condensing unit is greatly increased. In addition to increasing the efficiency of the condenser and the evaporator, this system also greatly reduces the necessity of adjustments and service typical to the expansion valve, evaporator refrigerant control systems.

Other objects and advantages of the invention will become apparent and in fact pointed out in the following detailed description taken in connection with the accompanying drawings, wherein in corresponding reference numerals designate similar parts throughout, and in which,

Figure 1 is a vertical sectional view of the refrigerant control device,

Figure 2 is a fragmentary vertical sectional view of a modified form of the invention,

Figure 3 is a longitudinal horizontal sectional view of Figure 2 taken on line 3—3 thereof,

Figure 4 is a front elevational view of a still further modified form of the invention,

Figure 5 is a detail fragmentary view partly in section of the form of invention illustrated in Figure 4,

Figure 6 is a curve of a refrigerator employing a straight float valve control,

Figure 7 is a curve of a refrigerator employing an expansion valve, and

Figure 8 is a curve of a refrigerator employing the type of valve forming the subject matter of the present invention.

In the accompanying drawings wherein for the purpose of illustration there is shown preferred embodiments of the invention, and referring more particularly to Figure 1, the reference numeral 6 generally designates the evaporating chamber which is employed in refrigerating systems of the character previously described.

- In the usual manner one end of the evaporator chamber is provided with a closure plate 8, having secured therein and projecting into the upper portion of the evaporator a conduit 10 which 5 communicates with the tubing 12 connected to the condensing unit which is of standard design and construction. It will thus be seen that the evaporated refrigerant is transmitted to the condensing unit in this manner.
- 10 As will be observed, the closure plate 8 is provided with an inwardly projecting externally threaded nipple 14 having a longitudinally extending bore or passage 16 therein, the inner end of which has a valve seat 18. On the inner 15 end of the nipple 14 there is screw-threaded a cap 20 having a laterally extending integral arm 22 to which there is pivotally mounted through the medium of the pin 24 the arm 26 carrying the float 28. Also pivoted on the pin 20 24 is an upstanding support 30 to which the outer end of the needle valve 32 is pivotally mounted, the inner end thereof, as clearly illustrated, cooperating with the valve seat 18 to control the flow of refrigerant from the passage 16 25 into the evaporator chamber 6. On the upper side of the arm 26 there is arranged an integral upstanding ear 34 to which there is securely fastened by means of the screw bolt 36 an upstanding arm 38. An armature 40 is 30 securely fastened to the pivotally mounted arm 38 and has secured thereto and extending laterally therefrom an L-shaped arm 42. Spaced from the depending leg 46 of the arm 42 is a second depending leg 48 between which the upstanding arm 38 is movable. The limit of travel 35 of the upstanding arm 38 between the depending legs 46 and 48 is controlled through the medium of the adjustable set screws 50. To the inner side of the closure plate 8 there is fastened a laterally extending arm 52 which has disposed 40 on the free end thereof a magnet 54 and an L-shaped arm having a depending portion 56 spaced from the outer end thereof. It will thus be seen that the armature 40 is movable 45 between the end of the magnet 54 and the depending portion 56 of the L-shaped arm.
- The refrigerant liquid is carried from the condensing unit to the evaporator chamber 6 by 50 the tubing 56 which is connected to the shell 58 of the expansion valve 60 through the medium of the connector 62. (Extending laterally in the shell and communicating with the connector 62 is a closed end conduit 65 having a valve seat 66, the lower side thereof adjacent the closed end.)
- 55 The flow of liquid from the conduit 65 and consequently through the valve seat 66 into the chamber 63 of the shell is controlled through the medium of an adjustable needle valve 68 cooperating with the valve seat and controlled in the usual manner by means of the sylphon 70. It will be seen that the sylphon is suspended 60 centrally within the shell 58, the needle valve 68 being connected to the sylphon by means of a saddle arm 72. The upper portion of the 65 sylphon 70 is not only securely fastened within the shell 58, but is sealed against leakage through the medium of the screw-threaded cap 74. Thus, it will be observed that a pressure exerted on the sylphon 70 will raise the saddle arm 72 and consequently the needle 69 closing the valve seat 66. Similarly, a reduction of pressure 70 against the sylphon 70 will allow the spring 78 to close therein to exert a pressure in the opposite direction and open the needle 68 in the 75 valve seat allowing the refrigerant to pass from

the tubing 56 through the valve seat 66 into the chamber 63 of the expansion valve. Incidentally, it is to be noted that this operation is the usual operation of an automatic expansion valve which is commercially on the market today and can be adjusted by means of the set screw 80 to any predetermined pressure opening or closing desired. The expansion valve is connected by means of the conductor 82, as clearly illustrated, to the closure plate 8 which conductor is screw-threaded therein and communicates with the passage 16 in the nipple 14.

It is to be noted that the liquid from the tubing 56 and in the conduit 66 is under the usual condensing pressure and maintained in liquid form. However, at the needle valve 68 and the seat 66 a reduction in pressure is encountered and the liquid is turned into a vapor. This is the usual function of an expansion valve. However, the amount of liquid passed by the valve 20 and the amount changed to vapor is entirely dependent upon the surrounding temperature, so that there are times when only a small portion of the liquid is turned into vapor. As the liquid and vapor pass through the chamber 63 of the 25 expansion valve and the threaded connector 82 it comes in contact with the float valve seat 18 and the cooperating needle valve 32. Thus, it will be seen that the valve 32 controls the passage of the refrigerant from the expansion 30 valve to the evaporating chamber 6. When there is a sufficient liquid to maintain a level such as indicated by the dotted line "A" the float 28 is raised on the pivot 24 through the medium of the arm 26 which is pivoted thereto. It will 35 be seen that a rising movement of the float 28 conveys a forward movement to the upstanding arm 38 causing it to abut the screw 50 of the depending arm 48 bringing about a forward movement of the armature 40. Obviously, the 40 armature 40 is held by the depending magnet 54 in its rearmost position until the force of the magnetic attraction is overcome whereupon it is moved forwardly and brought quickly into abutting engagement with the permanent magnet 56 45 effecting a snap action or quick closing of the valve seat 14 by the needle valve 32. Thus, the magnetic attraction of the magnet 54 holds the armature 40 in position there against maintaining the needle valve 32 in forward position for 50 closing the valve seat 14.

As the refrigerant evaporates in the evaporator 6, the liquid level is lowered and will finally reach level B. Under these conditions, as the liquid 55 level is lowered due to the evaporating of the liquid, the upward pressure on the float ball 28 and the arm 26 is reduced and the float tends to drop, but due to the magnetic force between the permanent magnet 54 and the armature 40, the float movement is stopped when the arm 38 comes in 60 contact with the set screw 50 of the arm 46 and remains in this position until the downward pressure on the float 28 is greater than the magnetic force between the permanent magnet 54 and the armature 40. When this downward pressure 65 overcomes the magnetic force, the float 28 and the arms 26 pull the armature 40 in a direction opposite to the magnetic attraction towards the depending L-shaped end 56 quickly bringing the needle valve 32 upon its pivotal support 30 to a 70 fully open position. It will thus be seen that the float valve is now open and there is unrestricted passage for the liquid or vapor to enter the evaporator chamber 6 through the valve seat 14. However, it is to be noted here that the pressure 75

built up by the evaporation of the liquid will be transmitted through the passage 16 in the nipple 14 to the chamber of the expansion valve and consequently against the sylphon 70 which will hold the needle valve 68 of the expansion valve closed against its seat 66. As the pressure or temperature of the evaporator chamber rises to a predetermined setting of the condensing unit control mechanism, the condensing unit is started 10 and pulls the gas from the chamber 6 through the tubings 10 and 12 connected to the compressor, reducing the pressure in the evaporating chamber 6. As the operation of the condensing unit continues, the pressure is reduced in the 15 chamber 6 to a point where the pressure against the sylphon 70 is not great enough to hold the valve 68 closed against the seat 66, the needle valve 68 opens and allows pure liquid to enter from the tubing 56. As the liquid enters the chamber 63 20 of the expansion valve and the evaporator 6 it absorbs heat and evaporates, causing a rise in pressure against the sylphon 70, overcoming the spring tension of spring 78 and closing the needle valve 68 against its cooperating seat 66. This allows a 25 constant pressure to be maintained in the chamber of the expansion valve through the passage 16 and the expansion chamber 6. This constant pressure can be adjusted to any predetermined setting by the adjustment of the screw 80 and the 30 spring 78. It can readily be seen that as long as the float valve is held at the level B the pressure in the evaporating chamber 6 is maintained constant by the expansion valve 60. As the temperature of the evaporator 6 is reduced there will be 35 only sufficient heat to evaporate a certain portion of the liquid entering the chamber of the expansion valve and the liquid will be carried to the evaporator through the passage 16 raising the liquid above the level B which will increase the upward 40 pressure on the float 28 and arm 26, but due to the magnetic force between the armature 40 and the depending member 56, the float is held in a downward position until the upward pressure of the float is sufficient to overcome the magnetic 45 force between the armature 40 and the magnet 54 which will allow the armature to snap over against the magnet 54 through the contacting of the upstanding arm 38 with the set screw 50 at the same time closing the needle valve 32 against 50 its cooperating valve seat 18. At this time the level will be at A which is below the suction opening 68.

It is obvious that as the mechanism goes through a cycle of operations the float will snap 55 open the needle valve 32 as the liquid level in the evaporator 6 is lowered to level B and as the liquid level is raised to level A the float will snap shut the needle valve 32 against its cooperating valve seat 18. The location of levels A and B is 60 controlled by the adjustment of screws 50. Thus, it will be seen that the liquid level will always be between A and B levels in the evaporator during a cycle of operation. The operation previously described may occur one or more times during 65 the operation of the condensing unit. As the needle valve 32 closes, shutting off the passage of gas and liquid from the expansion valve 60, the pressure in the chamber 6 is reduced and because of the evaporation taking place during the cycle of 70 operation sufficient heat is removed from the evaporator to a point where very little liquid is vaporized. This will allow the condensing unit to reduce the pressure in chamber 6 to a predetermined point at which the condensing unit control mechanism is set to start the condensing unit 75

and the refrigeration system has completed one complete cycle of operation.

To more specifically explain the operation of the device, during the operation of one cycle, assume that the snap action float device is incorporated in an evaporator in the fixture requiring an evaporated temperature of 20° to maintain a fixture temperature of approximately 40°. In SO₂ it requires approximately 2½ pounds of evaporated pressure to maintain an approximate 20° 10 evaporator. Assume that the evaporator is of sufficient size to maintain the fixture temperature by 16 hours operation out of the 24. When the condensing unit is placed into operation the float chamber and the entire evaporator contains no 15 refrigerant, and shortly after the condensing unit is placed into operation the pressure in the evaporator will be reduced 2½ pounds. In the absence of liquid refrigerant in the evaporator the snap action float will be opened and when the 20 pressure has been reduced to approximately 2½ pounds the expansion valve will open and feed a sufficient amount of liquid into the evaporator to maintain a 2½ pound pressure, providing the condensing unit is of sufficient capacity to handle 25 the gas from this refrigerant when it is operated. In due time through the evaporation of the refrigerant the coil temperature will be reduced to approximately 20°, the temperature of the refrigerant at 2½ pounds pressure. The capacity of 30 the expansion valve must always be in excess of the refrigeration load so that when the coil reaches its temperature the refrigerant would gradually build up in the coil until it reaches the predetermined level "A" in the float chamber, 35 (Figure 1.) At this point the snap action mechanism cuts off the liquid supply from the expansion valve. The condensing unit continues to operate until the low pressure control mechanism, which is usually set about 2 pounds lower than 40 the setting of the valve, cuts off the supply of energy to the electric motor. The evaporator which is now approximately 20° in a 40° fixture continues to absorb heat which continues the evaporation of the liquid until the pressure is 45 built up on the low side to a point where it will operate the high limit setting of the low pressure control which will start the condensing unit on another cycle. The snap action float may or may not have yet opened when the condensing unit 50 starts. However, after a few minutes of operation sufficient liquid may be drawn from the evaporator to drop the liquid level before the pressure has reached the low pressure control setting. If sufficient liquid is not drawn from the evaporator 55 by the time it reaches the low pressure control setting a short cycle will result. If, however, it does draw sufficient liquid from the evaporator so that the float valve opens a regular cycle will be the result. 60

Figures 6, 7, and 8 are curves showing one cycle of back pressures for the two conventional types of refrigerant controls and of the type control covered by the present invention. The ordinate on these curves represent pressures from ten 65 inches of vacuum to ten pounds pressure. The abscissa represents time interval and is calibrated in minutes from 0 to 60. The cycle is controlled by a low pressure switch set to start the condensing machine at ten pounds pressure. The 70 cut out point of the switch varies with the different type of control, as the desired fixed temperature is reached with a shorter cycle with the float and expansion valve combination because of the higher average back pressure. These charts are 75

typical and are shown to illustrate the efficiency of the combination of the float and expansion valve system of the present invention over the two conventional types now in use.

Referring now to Figures 2 and 3, it will be seen that there is shown a modified form of the invention which performs in combination with the expansion valve substantially the same result as the previously described snap action switch, which utilizes a magnet for obtaining the snap action effect. In this form of the invention, as illustrated in Figures 2 and 3, the expansion valve is connected to the closure plate 8 as previously described, the header being provided with the projecting nipple 14 having on the inner end thereof a valve seat 18. A cap 106 is screw-threaded on the nipple 14 which has a laterally extending arm 108 to which there is secured by means of a screw bolt 110 a support 112. As clearly illustrated in Figure 3, the arm 108 is bifurcated at its free end and has extending therethrough a pin 114 on which there is pivotally mounted the upstanding support 116. To the free end of the support 116 there is pivotally supported a needle valve 120 slidable in the bore in the cap 106 and cooperating with its associated valve seat 18. Obviously, upon a rocking movement of the pivotally mounted arm 116, the needle valve is moved into and out of seating engagement with its cooperating valve seat 18. As clearly illustrated, the pin 114 projects beyond the outer sides of the bifurcated ends of the arm 104 and has pivotally mounted thereon the arms 120 to which there is secured and not shown the usual float ball for controlling the upward and downward movement thereof.

As shown in Figure 2, the support 112 at its free end is provided on each side thereof adjacent the end with upstanding ears 122 carrying the transversely disposed pin 124 on which there is pivotally mounted the U-shaped member 126. It will be observed that the arms 128 of the U-shaped member are provided with set screws 130 and have disposed therebetween a transversely extending pin 132 disposed in the arms 120. Obviously, upon upward and downward movement of the arms 120, one or the other of the free ends of the set screws 130 are brought into contacting engagement therewith to the end that the U-shaped member 126 is moved about its pivot 124. Extending laterally from the bight portion of the U-shaped member 126 is an integral arm 140 having its free end sharpened to a substantially knife edge as at 142.

As clearly illustrated, to the outer side of the pivotal upstanding support 116 there is secured an L-shaped arm 144, the depending portion 146 thereof being bent outwardly providing a laterally extending arm 148, the free end of which is formed with a knife edge. Between the knife edges of the arms 140 and 148 as shown there is arranged a substantially horseshoe-shaped spring 150.

In operation it will be apparent that as the arm 120 is moved in a vertical plane by the rise and fall of the refrigerant, the pin 132 will contact one of the adjustment screws 130 and rotate the U-shaped member 126 around its pivot causing the knife edge of the arm 140 to move up or down. Thus, when the arm 120 is moved up pin 132 will contact the upper adjustment screw 130 and move the U-shaped member 126 around its pivot lowering the knife edge end of the arm 140 placing the knife edge end below the center line of the pin 115 on which the upstanding support 116 is pivotally mounted.

This will cause a pressure due to the expanding of the spring 150 against the member 148 which will move arm 144 and support 116 forwardly causing the needle valve to move forward and close against its seat 18. With the needle valve 120 in seated position, the passage 16 in the nipple is closed. When the level of the liquid in the evaporator lowers the float on the free end of the arm 120 (not shown), the arm 120 will pivot about its pin 114 lowering the pin 132 bringing it into contacting engagement with the lower adjustment screw 130 transmitting pressure to the arm 140 rotating the arm 140 in a counter-clockwise direction. This will raise the knife edge on the arm 140 until it passes the center line of pins 115 and 124 where it will release the spring pressure of spring 150 in a downward direction against the knife edge of the arm 148 which will rotate the support 116 in a counter-clockwise direction pulling the needle 120 away from its seat 18 opening the passage 16. Obviously, the movement of arm 120 and arm 140 will not be transmitted to the needle valve 120 until the knife edge of the arm 140 goes past the center line of the two knife edges and the center line of pins 115 and 124 at which point the needle valve 120 snaps open or closes in accordance with the direction of movement of arm 120. Clearly, this snap action type of float valve when employed and combined with an expansion valve as previously described with respect to the magnetic type illustrated and described in Figure 1 functions in the same manner and it is not thought necessary to again describe the cycle of operation.

Referring now to Figures 4 and 5, it will be seen that there is shown a further modified form of the invention which utilizes an electrically controlled valve in combination with an expansion valve which is operated through the medium of a float, the valve being actuated in a snap action manner.

As illustrated, the expansion valve 150 which is of the usual type employed such as described with respect to Figure 1, is connected to the header 152 of the evaporator (not shown) by means of the connection 154. To the nipple of the header 152 there is screw-threaded a cap 156 having a laterally extending arm 158 thereon, to the free end of which there is pivotally mounted the L-shaped arm 160 carrying the float ball 162. To the free end of the upstanding arm 164 there is pivotally mounted a mercury bulb 166 having space contact members 168 therein adjacent one end thereof. As clearly shown, these contact members project inwardly in the bulb and upon rotation of the bulb in the proper direction the contact members 168 are adapted to be bridged by the mercury 170 therein for closing the same. Rotation of the bulb is effected by the depending arm 172 which is movable between the adjustment screws 174 arranged in projecting ears 176 on the arm 164. It will thus be seen that the movement of the bulb may be controlled through the medium of the adjustment screws 174 which limit the travel of the arm 172. Obviously, upon an upward or downward movement of the arm 160 through the medium of the float 162 which in the usual manner is controlled by the refrigerant the mercury bulb is rotated in one direction or the other to effect through the medium of the mercury an opening or a bridging of the contacts 168. The header 152 is provided with spaced bores therein through which extend the binding posts 178 which are in

sulated therefrom and to which the contacts 168 are connected by the conductors 180. The liquid refrigerant supply from the condensing unit is supplied by the conduit 132 which is connected to the expansion valve 150. Between supply conduit 182 and expansion valve 150 for controlling the supply of refrigerant to the expansion valve there is provided a solenoid actuated valve 184. As shown the solenoid valve is provided with a needle valve in the form of an armature 186 which cooperates with its valve seat 188. The needle valve 186 is normally maintained in its closed position through the medium of the spring 190 and is moved to open position upon energization of the solenoid 192. The winding of the solenoid is connected to contacts 168 and a source of electrical supply by conductors 194.

Obviously, as the arm 160 rises, the mercury bulb is rotated tilting the mercury in a forward direction allowing the mercury to break contact with the contacts 168 de-energizing the winding of the solenoid permitting of the closing of the needle valve against its valve seat and stopping the flow of the refrigerant to the expansion valve 150. When the liquid level in the evaporator lowers and the float 162 lowers the arm 160 the mercury in the bulb moves in a counter-clockwise direction allowing the mercury to bridge and close the contacts 168 energizing the winding of the solenoid raising or opening the needle valve permitting of the refrigerant to pass into the expansion valve 115. Thus, the combined action of this type of valves with the expansion valve is the same as previously described more in detail with respect to the valve shown in Figure 1, and it is not thought necessary again to describe the complete cycle of operation thereof.

It will thus be seen from the foregoing that there is provided a combined snap action float valve and expansion valve which insures a flooded condition of the evaporator at all times and insures the feeding of the refrigerant to the evaporator at a constant suction pressure at a predetermined setting during the time the float valve is open, thereby increasing the efficiency of the evaporator and the condensing unit and greatly reducing the necessity of adjustment and service in refrigerating systems of the compressor, evaporator type refrigeration.

While there is shown for the purpose of illustration preferred embodiments of the invention, it is to be understood that they are capable of various changes and modifications without departing from the spirit and scope thereof, and it is intended therefore that only such limitations shall be imposed thereon as are indicated in the prior art and the appended claims.

What is claimed is:

1. In a refrigerating system including a refrigerant evaporating chamber and a source of refrigerant supply, a supply line connecting said refrigerant supply to said chamber, a snap action opening and closing float valve arranged to control the flow from said supply line and a pressure control valve in said supply line.

2. In a refrigerating system including a refrigerant evaporating chamber, a source of refrigerant supply, a conduit communicating said refrigerant supply to said chamber, a snap action opening and closing valve arranged to control the flow from said conduit, said valve being controlled by the refrigerant level in said chamber, and a pressure controlled valve in said conduit.

3. In a refrigerating system including a refrigerant evaporating chamber, a source of refriger-

ant supply, a supply line connecting said refrigerant supply to said chamber, a snap action opening and closing valve arranged to control the flow from said supply line, said valve being controlled by the refrigerant level in said chamber, and a pressure controlled valve in said supply line between said snap action valve and the refrigerant supply.

4. In a refrigerating system including a refrigerant evaporating chamber and a source of refrigerant supply connected thereto, means for controlling the refrigerant from said supply to said evaporator chamber comprising a snap action opening and closing float valve controlled by the level of the refrigerant in the chamber, and a pressure controlled valve actuated by the pressure of the refrigerant supply and the pressure in the evaporating chamber through the snap action float valve.

5. In a refrigerating system including a refrigerant evaporating chamber, a source of refrigerant supply, a supply line communicating said refrigerant supply to said chamber, means for controlling the refrigerant in said chamber from said refrigerant supply comprising in combination a snap action opening and closing valve actuated by the refrigerant level in said chamber, and a pressure control valve in said supply line.

6. In a refrigerating system including a refrigerant evaporating chamber, a source of refrigerant supply, a supply line communicating said refrigerant source of supply to said chamber, means for controlling the refrigerant in said chamber comprising in combination, a snap action opening and closing valve actuated by the refrigerant level in said chamber, and a pressure control valve in said supply line between the refrigerant source of supply and the snap action valve controlled by the pressure from the refrigerant source of supply and the pressure in the evaporating chamber through the snap action opening and closing valve.

7. In a refrigerating system including a refrigerant evaporating chamber and a source of refrigerant supply, a supply line for conveying said refrigerant to said chamber, a float actuated valve arranged to control the flow from said supply line, said valve being controlled by the refrigerant level in said chamber, means for effecting a snap action opening and closing of said valve, and a pressure control valve in said supply line.

8. In a refrigerating system including a refrigerant evaporating chamber and a source of refrigerant supply, a supply line for conveying said refrigerant to said chamber, a magnetically actuated snap action opening and closing float valve arranged to control the flow from said supply line, said valve being controlled by the refrigerant level in said chamber, and a pressure control valve in said supply line.

9. In a refrigerating system including a refrigerant evaporating chamber and a source of refrigerant supply, a supply line for conveying said refrigerant to said chamber, a spring actuated snap action opening and closing float valve arranged to control the flow from said supply line, said valve being controlled by the liquid level in said evaporating chamber, and a pressure control valve in said supply line controlled by the pressure of the refrigerant supply and the pressure in the evaporating chamber.

10. In a refrigerating system including a refrigerant evaporating chamber and a source of refrigerant supply, a supply line for conveying

- said refrigerant to said chamber, means for controlling the refrigerant from said supply to said chamber comprising in combination, an adjustable snap action opening and closing float valve arranged to control the flow from said supply line, said valve being controlled by the level of the refrigerant in said chamber, and an adjustable pressure controlled expansion valve in said supply line.
- 10 11. In a compressor-condenser-expander refrigerating system, control means for the flow of the refrigerant comprising a low side float controlled valve, in series with a pressure control valve responsive to evaporator pressure.
12. In a compressor-condenser-expander refrigerating system, control means including means responsive to the liquid level in the evaporator in series with pressure controlled means responsive to evaporator pressure. 5
13. In a compressor-condenser-expander refrigerating system, control means including means responsive to the quantity of liquid in the evaporator in series with pressure controlled means responsive to evaporator pressure. 10

PAUL HAYMOND.
